UNITED STATES PATENT OFFICE

147,674

DESIGN FOR A STAND

Harriett Eva Levings, Centuria, Wis.

Application May 18, 1946, Serial No. 129,847

Term of patent 14 years

(Cl. D33—10)

To all whom it may concern:

Be it known that I, Harriett Eva Levings, a citizen of the United States, residing at Centuria, in the county of Polk and State of Wisconsin, have invented a new, original, and ornamental Design for a Stand, of which the following is a specification, reference being had to the accompanying drawing, forming part thereof.

The figure is a perspective view of a stand, showing my new design.

I claim:

The ornamental design for a stand, as shown.
HARRIETT EVA LEVINGS.
